UNITED STATES PATENT OFFICE.

HERMAN WESTLING, OF WATERTOWN, MASSACHUSETTS, ASSIGNOR TO CAMBRIDGE RUBBER COMPANY, OF CAMBRIDGE, MASSACHUSETTS, A CORPORATION OF MASSACHUSETTS.

DESIGN FOR AN OVERSHOE.

Application filed November 26, 1926. Serial No. 19,846. Term of patent 3½ years.

To all whom it may concern:

Be it known that I, HERMAN WESTLING, a citizen of the United States, residing at Watertown, in the county of Middlesex and State of Massachusetts, have invented a new, original, and ornamental Design for Overshoes, of which the following is a specification, reference being had to the accompanying drawing, forming part thereof.

I claim:

The ornamental design for an overshoe, as shown.

HERMAN WESTLING.
